UNITED STATES PATENT OFFICE.

SEBASTIEN OTTO ALFRED FIEDLER, OF PARIS, FRANCE, ASSIGNOR TO L'AUXILIAIRE
DES CHEMINS DE FER ET DE L'INDUSTRIE, OF PARIS, FRANCE.

MEANS FOR SUPPLYING STEAM-BOILERS WITH FEED-WATER.

1,391,308.

Specification of Letters Patent. Patented Sept. 20, 1921.

Application filed March 30, 1921. Serial No. 456,816.

To all whom it may concern:

Be it known that I, SEBASTIEN OTTO ALFRED FIEDLER, citizen of the French Republic, residing at Paris, in the Republic of France, have invented new and useful Improvements in Means for Supplying Steam-Boilers with Feed-Water, of which the following is a specification.

This invention has for its object an installation for effecting the supply, at very high temperatures of boilers of locomotives or of all generators.

The improved installation comprises the combination of a tandem pump which draws into one of its cylinders water taken from the feed water tank and forces the same into a water-heater, and draws into its other cylinder the highly heated water taken from the water-heater and forces the same into the boiler; a water heater and an expansion vessel placed on a level higher than both the level of the feed tank and the level of the hot water cylinder of the pump, said expansion vessel being at its upper part in communication with the atmosphere and being also in communication on the one hand, at its lower part with the water heater at the highest point which can be reduced at its upper part either directly with the feed water tank or with the pipe connecting the pump to said tank.

The accompanying drawing shows by way of example an installation according to the invention, as applied to a locomotive.

As shown in the drawing, the present disposition comprises:

A tandem pump 1.

A feed water heater 2 constituted by a condenser which may be either of the surface of the mixing type and may use either the exhaust steam of the engine or residual vapors, or hot gases.

An expansion chamber 3.

The suction inlet of the lower cylinder 4 of the tandem pump 1 is connected by the piping 9 with the feed water reservoir 6 of the tender 7 of the locomotive, or feed tank, and the delivery orifice of the said cylinder is connected by the piping 12 with the lower part of the heater 2.

The suction orifice of the hot water cylinder 5 of the tandem pump 1 is connected by the piping 13 with the upper part of the heater 2 and the delivery end of the said

hot water cylinder is connected by the piping 14 with the boiler 8.

The expansion chamber 3 is open at its upper part and its lower part is connected with the highest point reached by the water in the chest proper of the heater 2.

The chamber 3 also has its upper part connected either directly with the water feed tank 6 or with the piping 9 connecting the suction orifice of the water cylinder 4 with the water feed tank 6. The upper part of the expansion chamber 3 is also preferably closed by a strainer.

The orifice 11 by which the pipe 10 connecting the tank 6 with the expansion chamber 3 opens into this chamber, is constructed in funnel shape.

The expansion chamber 3 is situated at a level which is both higher than that of the water in tank 6 and that of the cylinder 5 of the pump 1.

The operation of the device is as follows:

The pump 1, through the intermediary of the cylinder 4, effects the suction of the feed water into the tank 6 and forces the same into the heater 2.

By means of the cylinder 5, the pump 1 forces into the boiler 8 the heated water. This water enters the cylinder 5 by reason of the pressure resulting from the difference between the level of the expansion chamber 3 and that of the cylinder 5, irrespectively of the position of the heater.

The pump 1 is so constructed that the volume of water which can be delivered by the cylinder 4 shall be greater than the volume of water delivered by the cylinder 5.

This disposition has the following effect:

1. It provides for the filling of the heater 2 and keeps this heater constantly filled.

2. It supplies an excess of water which provides for the filling of the expansion chamber 3 and therefore affords a sufficient pressure for the proper working of the cylinder 5, in spite of the high temperature of the water which is delivered by this cylinder.

The orifice of suitable funnel shape 11 which in in the present case is placed at the upper part of the expansion chamber 3, and the piping 10 connecting this orifice with the feed tank 6, have the effect of obviating all loss of water.

The expansion chamber 3 places the water in the heater 2 in communication with the

atmosphere and thus permits the discharge of the air and carbonic acid contained in the water.

The situation of this expansion chamber 3 at a higher level than that of the feed tank 6 and the pump cylinder 5 have the effect:

1. Of affording a sufficient pressure to provide for the good working of the cylinder 5, in spite of the high temperature of the water 10 which it delivers, and this irrespectively of the position of the heater with reference to the pump.

2. Of providing for the discharge of the overflow, thus avoiding all loss of water.

Having now described my invention, what I claim as new and desire to secure by Letters Patent is:

1. An installation for supplying steam boilers with feed water, comprising in combination a feed water tank, a tandem pump having a cold water cylinder and a hot water cylinder, a water-heater, an expansion vessel in communication with the atmosphere at its upper part, said expansion vessel being 20 located on a level higher than both the level of the feed tank and the level of the hot water cylinder of the pump, means connecting the inlet of the cold water cylinder of the pump to the feed tank and the outlet to the 25 water-heater, means connecting the inlet of the hot water cylinder of the pump to the water heater and the outlet to the boiler, means for connecting the lower part of the expansion vessel with the water heater at 30 the highest point which can be reached by the water in the latter and means for establishing a communication between the upper part 35 of the expansion vessel and the feed water tank.

2. An installation for supplying steam-boilers with feed water comprising in combination a feed water tank, a tandem pump having a cold water cylinder and a hot water cylinder, the cold water cylinder of the pump 40 having a delivery greater than that of the

hot water cylinder, a water-heater, an expansion vessel in communication with the atmosphere at its upper part, said expansion vessel being located on a level higher than both the level of the feed tank and the level 50 of the hot water cylinder of the pump, means connecting the inlet of the cold water cylinder of the pump to the feed tank and the outlet to the water-heater means connecting the inlet of the hot water cylinder of the pump 55 to the water heater and the outlet to the boiler, means for connecting the lower part of the expansion vessel with the water heater at the highest point which can be reached by the water in the latter and means for establishing a communication between the upper part 60 of the expansion vessel and the feed water tank.

3. An installation for supplying steam-boilers with feed water, comprising in combination a feed water tank, a tandem pump having a cold water cylinder and a hot water cylinder, a water heater, an expansion vessel in communication with the atmosphere at its upper part, said expansion vessel being 65 located on a level higher than both the level of the feed tank and the level of the hot water cylinder of the pump, means connecting the inlet of the cold water cylinder of the pump to the feed tank and the outlet to the 70 water heater, means connecting the inlet of the hot water cylinder of the pump to the water-heater and the outlet to the boilers, means for connecting the lower part of the expansion vessel with the water heater at the 75 highest point which can be reached by the water in the latter and means for establishing a communication between the upper part 80 of the expansion vessel and the feed water tank, said means embodying a pipe which opens into the expansion vessel by a flaring 85 funnel-like end.

In testimony whereof I have signed my name to this specification.

SEBASTIEN OTTO ALFRED FIEDLER.
